PARING KNIFE

Charles H. S. Mensch, Boyertown, Pa.

Application November 11, 1936, Serial No. 110,396

1. Claim. (Cl. 30—278)

This invention relates to paring knives and its general object is to provide a knife that can utilize discarded blades, preferably of the double edged type, in that the knife includes a holder 5 for detachably clamping a blade for use in a manner whereby the blade provides the cutting edges for the knife.

A further object is to provide a paring knife of the character set forth, which includes a 10 guard for one of the cutting edges to limit the depth of its cut, and the blade can be applied and removed in an easy and expeditious manner, yet casual removal or displacement thereof is practically impossible.

Another object is to provide a paring knife of 15 the character set forth, that is simple in construction, inexpensive to manufacture, and extremely efficient in operation, use and service.

This invention also consists in certain other 20 features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a top plan view of the paring knife 30 which forms the subject matter of the present invention.

Figure 2 is a similar view of the body section 35 of the blade holder, showing the arrangement of a blade with respect thereto in dotted lines.

Figure 3 is a similar view of the other section of the holder.

Figure 4 is a longitudinal sectional view taken through the knife.

Figure 5 is a sectional view taken approximately on line 5—5 of Figure 1.

Referring to the drawing in detail, it will be noted that the blade holder includes what may be termed a body section 1 that is provided with 45 a flat face having lugs 2 formed thereon to receive a blade 3 which is preferably of the double edged type, and while new blades can be used with my knife, I preferably use discarded blades or ones which are too dull for shaving.

Cooperating with the body section 1 is a companion section 4 which is rounded transversely to provide a concavity 5 extending longitudinally thereof to form a chamber for the lugs 2, as best shown in Figure 5, it being obvious that the sections are disposed in face to face relation and

against the blade for clamping the latter between the same in a manner which will be presently described.

The body section outwardly beyond the lugs 5 thereof and preferably parallel therewith, as shown in Figure 2, is provided with an opening 6 which is formed by slitting the metal and pressing the material outwardly from the slit, as shown in Figure 4 to provide an abutment 7 for a tongue 8 on the outer end of the section 4, 10 the tongue being received in the opening, and by that construction, it will be seen that the outer end portions of the sections are connected.

Each of the sections 1 and 4 have formed therewith shanks having flat inner faces, and 15 the shank 9 of the section 1 is longer than the shank 10 of the section 4, in that the shank 9 terminates in an exteriorly threaded stud 11 to be threadedly secured within the bore 12 of a handle 13 for the knife, the bore receiving both 20 of the shanks disposed in face to face relation with respect to each other, for cooperation with the connection at the outer ends of the sections and the lugs for clamping the blade between the sections against casual removal or displacement. 25

The body section 1 is provided with a slot 14 that extends longitudinally thereof adjacent one edge, for the passage of one cutting edge of the blade 3, as best shown in Figures 2 and 5, and the edge portion outwardly of the slot is 30 curved upon itself as at 15 to act as a guard for the blade edge to limit the depth of its cut.

The opposite side edges of the sections terminate flush with each other and the opposite blade edge extends beyond the same to be used 35 for cutting purposes, consequently it will be seen that both edges of the blade are put in use and provide cutting edges for my knife.

The outer end of the body section 1 is reduced to provide a substantially pointed portion 16 for 40 use in digging into vegetables or the like for removing undesirable portions thereof, and the portion 16 is preferably sharpened.

From the above description and disclosure of the drawing, it will be obvious that a blade can 45 be readily applied and removed with respect to the holder, merely by removing the handle from the shanks of the sections, which will allow the sections to be separated, but when the handle is threaded in position for use, the sections which 50 act in the capacity as jaws set up a viselike clamping action upon the blade, with the blade arranged to provide the cutting edges for the knife.

It is thought from the foregoing description 55

tha the advantages and novel features of the invention will be readily apparent.

It is to be understood that changes may be made in the construction and in the combination and arrangement of the several parts, provided that such changes fall within the scope of the appended claim.

What I claim is:

A knife comprising a holder for a razor blade of the double edged type and including substantially flat elongated jaw sections, an abutment struck from one of said sections and providing an opening therein adjacent the outer end thereof, blade opening receiving lugs on the latter section, a tongue formed on the other section and receivable in the section opening for engagement with the abutment for connecting the outer end portions of the sections together, a

shank for each section, a handle having a bore therein receiving the shanks for cooperation with the tongue, the abutment and the lugs for detachably securing the blade between the sections with the latter in clamping association therewith, one of said sections having a slot therein and extending longitudinally adjacent one side edge thereof for disposal of one cutting edge of the blade therethrough, the other cutting edge extending outwardly beyond the opposite side edges of the sections, the slotted section being reduced from adjacent to and toward its outer end to provide a substantially pointed outer portion therefor, and the slotted section being laterally and outwardly flared in rounded formation from the slot to provide guard means for the cutting edge that extends through the slot.

CHARLES H. S. MENSCH.
